FRED E. MAXFIELD, OF HOLYOKE, MASSACHUSETTS.

ROLL-BAR FOR PAPER-PULP ENGINES.

1,170,495.

Specification of Letters Patent.

Patented Feb. 1, 1916.

Application filed March 6, 1915. Serial No. 12,510.

To all whom it may concern:

Be it known that I, CHARLES IRVING WARE, a citizen of the United States of America, residing in the city of Holyoke, county of Hampden, and State of Massachusetts, have invented certain new and useful Improvements in Roll-Bars for Paper-Pulp Engines, of which the following is a specification.

10 This invention relates to improvements in roll bars for paper pulp engines which are used to beat the paper pulp.

My present invention is an improvement of the roll bar shown, described, and claimed 15 in Letters Patent of the United States, granted to me on May 17, 1910, numbered 958,708, upon an application filed November 24, 1909, Serial No. 529,676. The construction of roll bar in my aforesaid patent is 20 built up of three pieces, two of which are wrought iron with a steel blade located between the same. Experience has shown that this bar, unless very carefully constructed, will not be as rigid and firm as if the member which receives the steel blade is formed 25 from a single piece of metal.

As in my patent, above referred to, an object of the present invention is to expose as little as possible the inlaid steel blade to the 30 corroding or chemical action of the acids contained in the paper pulp which is being beaten, since it is a well-known fact that steel does not resist chemical action of the acids contained in the paper pulp as well 35 as iron.

My present invention, broadly stated, comprises a roll bar that is constructed from a single one-piece member of wrought iron or other suitable material having a longitudinal groove cut therein by any suitable means and locating in this groove the steel plate, the whole then being heated and welded together.

The invention will be fully described in 45 the specification and specifically pointed out in the appended claims.

In the accompanying drawings forming a part of the specification Figure 1 is a perspective view showing the one-piece wrought 50 iron bar having a longitudinal grooved cut therein, the upper or abrasive edge of the bar being formed with two parallel oppositely disposed portions; Fig. 2 is a perspective view, similar to Fig. 1, but show-

ing the steel bar located in the groove of 55 the wrought iron bar; and Fig. 3 is a detail view of the steel blade before insertion in the grooved bar.

Referring to the drawings in detail: 1 60 designates the wrought iron bar member in which is first cut the longitudinally arranged groove 2. This groove, as will be observed, is formed with an inclined portion 3 which terminates in a sharp angular part 4. The width of the other portions of the groove is 65 the same throughout its length as will be observed from Fig. 1. After the groove has been carefully cut, the steel blade or plate 5, shown in Fig. 3, is then inserted in the groove. The shape of this blade, in cross- 70 section, corresponds exactly with shape of the groove. After the insertion of the steel blade 3 in the groove of the bar, the whole is then brought up to a welding temperature, when the bar is forged into the shape 75 shown in Fig. 2 producing in effect a one-piece integral mass. The forging operations necessarily reduce the thickness of the bar at the beating edge 6 and also result in making the blade tapering. The side portions 80 7 and 8 are substantially the same in thickness as the blade after the forging operations are completed. The purpose of the inclined portion 3 and angular part 4 of the groove is to effect a perfect weld or union 85 between the bar and the inserted blade. It will also be observed that on account of the thickness of the side portions 7 and 8 being the same as the inserted blade that, when 90 the bar as a whole wears down from use, the same relative thickness between the blade and the portions 7 and 8 will still remain. It should be stated that, as the bar wears away the thickness of the blade also increases and, on account of this increase in 95 thickness, the wear will be very much slower.

The particular and definite advantages of making a roll bar by this process instead of by the process shown in my aforesaid patent is that the process therein described is very 100 much stronger and rigid, being in fact a one-piece member. This method of manufacture substantially covers up all of the surface of the inserted plate 5 and prevents the same from coming into contact with the 105 acids contained in the pulp.

The present invention obviates the possibility of the steel blade from chipping off

- at its edges when the bar is in use, the small particles of steel producing an inferior quality of paper, as is well known. Further, on account of the blade 5 being thoroughly 5 welded to the bar 1, there is no possibility of its working loose during the operation of the machine. The bar is rotated in the direction of the arrow 9, that is to say, the advancing side of the bar is the smooth side.
- 10 The above description relates to a roll bar composed of steel and wrought iron, but it is to be distinctly understood that I do not limit myself to the use of any particular kind of materials, as any other materials 15 that will accomplish the same results in equally as good manner may, of course, be substituted or used.

It is also within the province of my invention to vary the dimensions of the steel 20 blade and the groove 2 therein, as readily understood. It is also evident that on account of the tapered shape of the steel plate after welding that the possibility of the 25 plate becoming dislodged is thoroughly prevented, since the tapered part extends toward the beating edge 6 of the bar.

It has been found in practice that the soft 30 iron members 7 and 8 serve to draw out the fibers of the pulp much better than where the hardened plate alone is used.

The tapered product necessarily prolongs 35 the life and usefulness of the bar since, as stated, the tapered form of the inserted plate furnishes a thicker steel for beating up the pulp, as it wears down.

What I claim is—

1. A roll bar for paper pulp engines, comprising, a one-piece member formed with a groove therein, and a plate located in the

groove and integrally secured to said member.

2. A roll bar for paper pulp engines, comprising, a wrought iron one-piece member formed with a groove therein, the upper outlet end of the groove having side-portions of substantially equal thickness, a hardened plate located in the groove and having its outer edge flush with the outer edge of the side-portions and substantially of the same thickness as one of said side portions.

3. A roll bar for paper pulp engines, consisting of two members, one having a longitudinal groove therein and the other a steel plate of corresponding shape contained in the groove, the lower and upper ends of the groove and the inserted plate being of unequal thickness and one of the side portions of the grooved member which engages one of the sides of the inserted plate being of the same thickness as the inserted plate, as described.

4. A roll bar, for paper pulp engines, comprising, a grooved one-piece member, the groove having its inner end formed with an inclined surface, a steel plate inserted in the groove and integrally secured to the wrought iron member, one of the portions of the wrought iron member adjacent to the inserted plate being of equal thickness, as said plate as described.

5. A roll bar for paper pulp engines, comprising, a one-piece member and a tapered plate located therein.

CHARLES IRVING WARE.
